(57) **CLAIM**

The ornamental design for a bottle, as shown and described.

DESCRIPTION

FIG. 1 is a perspective view of a bottle showing our new design;

FIG. 2 is a right side view thereof, the left side view a mirror image thereof;

FIG. 3 is a front view thereof, the back side view a mirror image thereof; and,

FIG. 4 is a top view thereof.

The broken lines in the drawings depict portions of the bottle that form no part of the claimed design.
